FISH LURE

Marjorie J. Lowrey, 1235 81st Ave., St. Petersburg, Fla.

Filed Jan. 15, 1964, Ser. No. 78,210

Term of patent 14 years

(Cl. D31—4)

FIG. 1 is a top plan view of a fish lure embodying my new design;

FIG. 2 is a side elevational view of the fish lure;

FIG. 3 is a front elevational view of the fish lure;

FIG. 4 is an elevational view of the opposite side of the fish lure to that shown in FIG. 2;

FIG. 5 is a back view in elevation of the fish lure; and

FIG. 6 is a bottom view of a fish lure.

I claim:

The ornamental design for a fish lure, as shown.
